SOLOMON SQUIER AND HORACE SQUIER, OF MONSON, MASSACHUSETTS.

Letters Patent No. 70,912, dated November 12, 1867.

IMPROVEMENT IN MACHINES FOR PRESSING BONNETS.

The Schedule referred to in these Letters Patent and making part of the same.

TO ALL WHOM IT MAY CONCERN:

Be it known that we, **SOLOMON SQUIER** and **HORACE SQUIER**, of Monson, in the county of Hampden, and State of Massachusetts, have invented a new and improved Machine for Shaping and Pressing Hoods; and we do hereby declare that the following is a full, clear, and exact description thereof, which will enable others skilled in the art to make and use the same, reference being had to the accompanying drawings, forming part of this specification.

This invention relates to a machine for shaping and pressing hoods, and consists of a hollow metal block, of the required shape, into which a heater is inserted, or the same may be heated by a gas-jet, or lamp. This block is hinged upon a stand, midway between two uprights, which work in grooves in the side of the frame, and are surmounted by a yoke-piece, supported by springs or weight. A jointed presser is suspended loosely from the centre of the yoke by an adjustable suspension rod, metal lip-plates overlapping the joints. The divisions of the presser are connected by pressure-bars to the pressure-frame, at bottom of the yoke-piece, which, when the machine is operated, press the divisions together over the hood. Heaters are also placed at the shoulder of each wing of the presser. The whole is operated by a lever, attached to a bar, connecting the bottom of the uprights, which, drawing down the yoke upon the springs, forces the presser down upon and over the hood, placed upon the block. In the accompanying drawings—

Figure 1 is a front vertical section along the line *z z* of fig. 2, and

Figure 2 is a transverse section along the line *y y* of our improved machine.

Similar letters of reference indicate like parts.

A A are the stand on which the hollow metal block B is hinged, at *b*. *b'* is a heater, inserted in the block B. C C are supports, working in grooves in the sides of the frame A, and surmounted by the yoke-piece D, supported by the spiral or other springs E E; A, C, D, and E, comprising what we call the pressure-frame. The divided or jointed presser F f is hung on pivots to the adjustable suspension rod G, which passes through the yoke-piece D, and is held by the nut *g*. Lip-plates *m n*, on the inner surface of the wings, overlap the junction lines of the jointed presser F f, preventing a seam upon the hood, and securing uniformity of pressure. Supplementary heaters *h h* are set on the jointed presser, on the line of the seam joining the crown to the body of the hood. The pressure-bars L are pivoted to the uprights of the pressure-frame at *l l*, and to the jointed presser at *l' l'*. The uprights are united at their base by the bar *k*, which is attached at *w* to the lever of the second order, M, having its fulcrum on the cross-bar N, pivoted in the standards of the frame at O, or the cross-bar may be fixed at O, and the lever M pivoted on it at N.

To operate the machine, the hollow block is drawn back upon its hinge, the heater inserted. The block is then raised upon its hinge into place beneath the divided or jointed presser F f; the hood is then placed on the block, the supplementary heaters *h h* are placed on the shoulders of the presser, and the power applied to press down the long arm of the lever M, thereby drawing down the yoke-piece D upon its prongs E, carrying with it the jointed presser F f over the hood. When the presser reaches the stand of the frame A, the power continuing to be applied, draws the yoke down the adjustable suspension rod G, straightening in its descent the pressure-bars L, and forcing the divisions of the jointed presser together, the lip-plates *m n* overlapping their lines of junction. On the power being withdrawn from the lever M, the recoil of the springs E forces up the yoke-piece D, carrying with it the presser F f off the hood. The power, whether hand, steam, or of any other kind, may be applied to press the yoke-piece D down upon its springs in any other convenient method. By the employment of a slide-hinge at *b*, different-sized blocks may be used at different times to press hoods of varying proportions by the same machine, without changing the jointed presser.

What we claim as new, and desire to secure by Letters Patent, is—

1. The combination of the jointed presser F f, pressure-bars L, pressing-frame A C D E, block B, heater *b'*, suspension rod G, lip-plates *m n*, and supplementary heaters *h h*, as herein described for the purpose specified.

2. The block B, when attached to the frame A, by a slide hinge, *b*, so that different-sized blocks may be used to press hoods of varying proportions, by the same machine, without changing the jointed presser, as herein set forth.

SOLOMON SQUIER,
HORACE SQUIER.
